(57) **CLAIM**

The ornamental design for a ClickLine working element, as shown and described.

DESCRIPTION

FIG. 1 is a right side perspective view of a ClickLine working element in accordance with the new design;

FIG. 2 is a right side elevation view thereof, the left side elevation view being a mirror image thereof;

FIG. 3 is a top plan view thereof;

FIG. 4 is a bottom plan view thereof;

FIG. 5 is a front elevation view thereof; and,

FIG. 6 is a rear elevation view thereof.

The broken lines immediately adjacent the claimed areas represent the bounds of the claimed design while all other broken lines are directed to environment and are for illustrative purposes only; the broken lines form no part of the claimed design.

1 Claim, 5 Drawing Sheets

FIG. 3

FIG. 4

FIG. 5

FIG. 6
